UNITED STATES PATENT OFFICE.

FRIEDRICH WILHELM LÄSSIG, OF CHEMNITZ, GERMANY.

BORING APPARATUS FOR EMBROIDERING-MACHINES.

1,107,622.

Specification of Letters Patent. Patented Aug. 18, 1914.

Application filed September 10, 1910. Serial No. 581,501.

To all whom it may concern:

Be it known that I, FRIEDRICH WILHELM LÄSSIG, a subject of the Emperor of Germany, and a resident of Chemnitz, in the 5 Empire of Germany, have invented certain new and useful Improvements in Boring Apparatus for Embroidering-Machines, of which the following is a specification.

This invention relates to a boring apparatus for embroidering machines.

The drawings illustrate the manner in which the invention is put into practice.

Figure 1 shows a side-view of the new boring apparatus in connection with a frame 15 of the embroidering machine. Fig. 2 shows the same parts as Fig. 1, seen from the front. Fig. 3 shows the boring apparatus apart seen from the rear. Fig. 4 is a horizontal cross section on $a-b$ of Fig. 1, but illustrated on a larger scale than Fig. 1. Figs. 5 to 8 are diagrammatic views illustrating the operation of certain of the parts.

In the frame 1, 2, 3 the two shafts 4 and 5 are capable of being turned around.

25 4 is the driving shaft and 5 is the shaft of the intermediate belt gearing. Several levers 7 are fixed on the two shafts 6, of which the drawing (see Fig. 2) shows only one in the upper row and one in the lower row. In Fig. 1 the levers 7 are not visible, because they are covered by the levers 11, which are of the same shape and dimension, as the levers 7. Each lever is connected with a moving slide rod 8. On the line 30 $x-x$ in Fig. 1, embroidery is stretched in a vertical plane. A large number of boring tools 10 are fixed in rows to long rails, 9. The rails 9 are fixed to the rear ends of the said slide rods 8. The upper boring driving shaft 6 is positively connected with the lower shaft 6 by levers 11 connecting rods 12, arms 14 and 15, which are fixed to the intermediate shafts 13, and by the vertical coupling rod 16. On the shaft 17 there is 40

45 suspended a pendulum-hanger-frame 18 with its two naves 19, 20 which is loose and capable of being turned around. At its lower end 21 there is fixed the journal bolt 22 which is immovably fixed and on which 50 there are the belt pulley 23 and the eccentric disk 24 which are loose and capable of being turned around. The two parts 23 and 24 are connected together. The eccentric disk 24 is rotatory in the eccentric strap 25, 55 which forms the lower end of the eccentric rod 26. The eccentric rod 26 consists of a

long lower arm and a shorter upper arm. Between the two parts it is slotted so that it can slide up and down on the link block 27 and swing to and fro at the same time around the shaft 17, when the eccentric 24 moves about its axle 22. The moving rod 29 being directed obliquely downward is connected with the highest point 28 of the eccentric rod 26, and its lower end is formed as a slide rod 30 fitting snugly in a guide bracket 31. The guide bracket 31 is movable about a horizontal pivot fixed in the frame 1. The rod 29, 30 has a box-shaped extension 32 (see Fig. 1 and Fig. 3) in which there is a rotatory cube 33. The cube 33 has a transversal hole, in which the cylindrical lever 34 is slidable to and fro. The lever 34 is rigidly fixed to the shaft 17. The eccentric rod 26 is supplied with a handle 35. To the frame 1 is fixed an adjusting curve 36, in which there are holes to put in a stop bolt in order to limit the oscillations of the eccentric rod 26.

On the shaft 17 are arranged two belt pulleys 37, 38 which are loosely rotatory, Fig. 4. The axle of the pulley 38 is movable. The two pulley rims 37, 38 are formed as a cone-coupling. The nave of the pulley 38 has a groove 39 running around it and into which gears the roller 40 of the lever 41, 42. A spiral spring 43 operates to compress the two parts 38 and 37 of the cone-coupling. In the frame 1 there is immovably fixed a horizontal bolt 44, on which is placed the lever 45, 46 (see Fig. 1, Fig. 3 and Fig. 4) which is loosely rotatory. The two ends of the levers 45 and 42 touch each other at their sloped faces. When the lever 45, 46 is revolved the oblique face of lever 45 presses the oblique face of lever 42 to one side and the cone-coupling is opened. The belt drive is effected from the intermediate shaft 5 by way of the two belts 49 and 47. On the shaft 17, Fig. 2, the lever 50 is rigidly fixed, and is movably connected by the drawing rod 51 with coupling rod 16.

The practice of using the boring apparatus as described is as follows, considering Figs. 5 to 8. Fig. 5 shows the arrangement of the mechanism when the apparatus is not in operation. At such time the eccentric rod 26 has been swung to one side by means of the handle 35 and a securing bolt inserted into the hole 52 visible in Fig. 1. 110 The eccentric rod 26 has consequently pressed back the lever 46 (Fig. 1 and Fig.

3), so that the upper end 45 of the lever 46 presses against the lever 42 (see Fig. 4) and the cone-coupling 37, 38 is ungeared. In that position of the parts (see Fig. 5) the 5 boring tools 10 are drawn back from the embroidery material represented by $x-x$. When the boring is to be begun, the securing bolt is drawn out from the hole 52 and the eccentric rod 26 is swung in the direction 10 of the arrow 53, Fig. 1, as far as it is necessary for the dimension of the holes to be bored. Inasmuch as the boring tools 10 taper, the holes in the embroidery stuff $x-x$ become larger, the deeper the boring tools 15 are pressed inward. For instance when Fig. 5 is compared with Fig. 7, it will be seen that in Fig. 7 the boring tools 10 extend farther into the stuff $x-x$, but are far distant from it in Fig. 5, because in Fig. 7 the eccentric rod 26 has been swung to the right 20 and in Fig. 5 to the left.

Between Fig. 5 and Fig. 6 there is the distinction that (see also Fig. 1) in Fig. 5 the eccentric 24 stands above the axle 22, but in 25 Fig. 6 under the axle. Consequently the boring tools 10 in Fig. 5 are also far distant from the stuff $x-x$ and in Fig. 6 extend into it. There is also the same distinction between the Figs. 7 and 8, as explained before.

From all the foregoing it results that the boring tools 10 very quickly go into and out of the stuff $x-x$ when they are pushed to and fro by the quick revolution of the belt 35 pulleys 23, 37 and secondly that the bored holes turn out deeper or less deep, in proportion as the eccentric rod 26 has swung more in the direction of the arrow 53 (Fig. 5) or more in the direction of the arrow 55. 40 If it is desired not to bore quickly with mill power, but to work slowly and carefully when making quite fine embroideries, the belt 49 (Fig. 1) can be thrown off and the handle moved to and fro with the hand in 45 the direction of the arrows 53, 55.

Heretofore boring apparatuses were not interchangeable from hand driven to power driven, but were either driven by hand or by power according to the construction of each 50 particular machine, and were not so constructed as to be convertible from hand driven to power driven or vice versa as might be desired.

Another valuable quality of the new boring-apparatus is that the workman can exactly feel by touch of the hand on 55, even when the boring-apparatus is driven with mill-power, whether the boring tools 10 meet with a hard obstacle. Until now it was 60 a great annoyance that the mill-power drove the boring tools against the embroidery

stuff $x-x$ by great force, just as much whether the points of the boring tools pierce into a thin soft stuff or whether the points of the boring tools meet with the thickly 65 stuffed places of the embroidery pattern. In the latter case fractures either of the boring tools or of the machine often happened, or the workman might thereby meet with an accident. All these imperfections have 70 been removed by the present invention.

What I claim and desire to secure by Letters Patent is:—

1. In a boring apparatus for embroidering machines, the combination with the boring points, of a shaft connected with the boring points, a rod mounted to rock and to slide about said shaft, a rod hinged to said rocking rod, and means connecting said hinged rod to the shaft to reciprocate the 80 boring points, substantially as described.

2. In a boring apparatus for embroidering machines, the combination with the boring points, of a shaft connected with the boring points, an eccentric-rod slidable and 85 rotatable about said shaft, a rod hinged to said eccentric-rod and a lever connected to said shaft and having a sliding and rocking connection with said hinged rod whereby movement is transmitted from the eccentric 90 rod to the shaft, substantially as described.

3. In a boring apparatus for embroidering machines, the combination with the boring points, of a shaft connected with the boring points, an eccentric-rod slidable and 95 rotatable about said shaft, a rod hinged to said eccentric-rod, a rocking guide in which the lower end of the hinged-rod is slidable, and a lever connected to the shaft and having a sliding and rocking connection with 100 the hinged-rod for the transmission of movement from the eccentric-rod to the shaft, substantially as described.

4. In a boring apparatus for embroidering machines, the combination with the boring-points of a shaft connected with the boring points, a swinging frame carrying a belt pulley and eccentric, drive-pulleys, one of which is connected with the belt-pulley of the swinging-frame, an eccentric-rod 110 connected with the eccentric of the swinging frame, a rod hinged to the eccentric-rod, a lever connecting said hinged rod and the abovementioned shaft, and means co-acting with the drive-pulleys and eccentric 115 rod to unclutch the drive-pulleys, and stop the shaft at a predetermined movement of the eccentric-rod, substantially as described.
